Willie Maguire

ATTORNEY

UNITED STATES PATENT OFFICE.

STUART B. MOORE, OF HOUSTON, TEXAS.

ROADWAY.

1,383,228.

Specification of Letters Patent. Patented June 28, 1921.

Application filed March 23, 1920. Serial No. 368,067.

To all whom it may concern:

Be it known that I, STUART B. MOORE, a citizen of the United States, and a resident of Houston, in the county of Harris and State of Texas, have invented certain new and useful Improvements in Roadways; and I do hereby declare the following to be a full, clear, and exact description of the invention, such as will enable others skilled in the art to which it appertains to make and use the same.

The successive steps of making a roadway in accordance with my invention are illustrated in Figures 1 to 4. Fig. 5 shows one of the expansion joints between sections of the roadway.

In carrying out my invention I first form the earth surface as shown in Fig. 1, a grading machine being used to create a convex base or "water shed" 1 and side ditches 2. I then cut the base longitudinally to form the dove-tailed grooves 3 with convex inner walls 3^a, as seen in Fig. 2. For practical economy the earth removed in forming these grooves may be piled as at 4 and kept for subsequent use. At intervals of about 20 feet the roadway is cut transversely to form a series of spaced apart sections, as shown in Fig. 5.

The third step is shown in Fig. 3. I lay rods 5 lengthwise in the grooves 3 and place side forms in position and slightly roughen the surfaces 3^a. I then pour the concrete to constitute the rails 6 having channels 7 in their tread surfaces and upward serrations on their outer sides and having the rods 5 embedded in them, and their under faces concaved and roughened as at 8 to aid in maintaining them in position and conform to the convex surfaces of the grooves 3. The side forms may then be lifted out. As shown the tops of the rails project well above the base 1 of the graded surface. I then pour an adhesive composition 9, such as bitumen or asphalt sizing, over the outer sides and tops of the rails and the earth previously piled at 4 is used to fill in outside of and between the rails to form a layer 10 terminating in depth about 3 inches below the tops of the rails.

Fig. 4 shows the fourth step consisting of a three inch layer 12 of broken stone or screened gravel upon the layer of earth 10 and upon the rails, taking particular care to allow this stone or gravel to run down

against the outer faces of the rails in contact with the adhesive composition 9.

Upon the structure thus far completed I pour a hot asphalt or bitumen filler and allow it to percolate through the interstices of the subjacent layers 12 and 10. This binds the supporting foundation into a mass which, in addition to firmly holding the rails in place, is impervious to moisture.

It is not necessary that the concrete rails 6 be formed at the roadway. They may be made separately with the rods 5 embedded in them and be inserted lengthwise in the grooves 3 of their respective sections. It is essential, however, that expansion joints 70 be provided between the several sections. As appropriate means for attaining this purpose I cause the reinforcing rods 5 to project from one end of a rail section and form the other end of the section with holes 13 to receive the projecting ends of the rods of the adjacent section. The projecting portions of the rods are coated heavily with a hot asphalt solution so that they will not adhere to the rail unit into which they extend. This 80 permits of longitudinal motion resulting from expansion or contraction but prevents lateral torsion, thus maintaining the alignment of the rail.

The foregoing applies when the rail is 85 poured as well as when previously formed. In the former event the rods are coated with the asphalt solution at the points where they bridge the spaces between sections and extend into adjacent sections.

The spaces between adjacent sections as laid need not be more than a quarter of an inch in order to allow of sufficient expansion.

Experience has shown many advantages 95 of concrete vehicle tracks in a roadway. Primarily it defines the normal area of travel. It has been found very difficult to keep the rails in place and maintain the proper gage and elevation. This is mainly due to moisture penetrating the bed or foundation which supports the rails. Rails which are simply laid upon the earth foundation, even though they have auxiliary members between them and the earth, fail to meet the requirements. 100

Bitumen filled or "Tarvia" roads marked a distinct improvement because they shed water and maintain the underlying earthy material dry and compact. These roads however are not hard and durable; they are soft 110

and they wear rapidly, creating holes through which water passes and disintegrates the underlying foundation. Depressions result into which the top layer sinks, causing an undulating riding surface. In warm weather the composition wrinkles, making a rough surface.

The principle of a hard substance to take the wear while adequately supported in a soft substance is well known and may be successfully invoked in roadways provided sufficient bond be employed and leakage of water be prevented. By the means I have shown and described a cement wheel way is firmly bonded in a water proof asphaltic concrete and the shape of the rails constituting the wheel way is such as to tend to tighten the bond. The relatively slight cost of maintenance is confined to the joint between the cement wheel way and the supporting asphaltic concrete.

By means of the joints between the rail sections adequate provision is made for contraction and expansion.

I claim as my invention:

1. In a roadway, a vehicle wheel way comprising rails of hard material such as cement, and asphaltic concrete covering said rails.
2. In a roadway, a vehicle wheel way comprising rails of hard material such as cement, said rails formed with sloping sides which are roughened on their outer surfaces, and asphaltic concrete forming a supporting bond for said rails and bearing upon the sides thereof.

3. In a roadway, a cement vehicle wheel way comprising rails, each rail having an asphaltic sizing applied to its outer surfaces, and an asphaltic concrete covering said rail.

4. In a roadway, a road bed having grooves cut in its surface, in combination with rails seated in said grooves, the sides of said rails being coated with an asphaltic sizing, a layer of earth partially covering the sides of said rails, and a superposed layer of asphaltic concrete completing the covering of said rails.

5. In a roadway, a road bed having dove-tailed grooves with convex bases cut in its surface, in combination with dove-tailed rails seated in said grooves and having their inner walls concaved, the sides of said rails being coated with an asphaltic sizing, a layer of earth partially covering the sides of said rails, and a superposed layer of asphaltic concrete completing the covering of said rails.

6. In a roadway, a road bed having grooves with convex bases cut in its surface, in combination with substantially triangular rails seated in said grooves formed with channels in their tread portions and having concaved roughened inner walls seated in said grooves, the sloping sides of said rails having upward projecting serrations, a layer of asphaltic sizing covering said rails and asphaltic concrete over said sizing.

In testimony whereof I have signed this specification.

STUART B. MOORE.
